UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

SHEAVE SUPPORT.

Application filed March 9, 1922. Serial No. 542,380.

To all whom it may concern:

Be it known that I, ROBERT H. BEAUMONT, a citizen of the United States, residing in Radnor, Delaware County, Pennsylvania, 5 have invented certain Improvements in Sheave Supports, of which the following is a specification.

My invention relates to certain improvements in rope sheaves used to carry the rope 10 at the back of a piling floor on which a scraper is used to pile material on the floor or to remove material from the pile.

One object of the invention is to design the sheave so that it will be counterbalanced 15 and will be properly supported not only when the rope is taut, but also when it is slack.

A further object of the invention is to design the support so that it will accommodate 20 itself to different angles, according to the reeving of the rope.

A still further object of the invention is to provide a rigid lower brace, which is 25 swiveled in its support on a wall, or other fixed structure.

While the invention is especially adapted 30 for use in a storage plant in which there is a back wall, it will be understood that the device can be mounted on a post, or similar support, without departing from the essential features of the invention.

In the accompanying drawings:

Fig. 1 is a view, in elevation, showing my 35 improved sheave support attached to the back wall of a coal piling floor;

Fig. 2 is a sectional plan view on the line 2—2, Fig. 1;

Fig. 3 is a sectional view on the line 3—3, Fig. 1;

Fig. 4 is a detached perspective view of 40 part of the sheave support; and

Fig. 5 is a view, partly in section, showing the lower bearing for the brace.

Referring to the drawings, 1 is a wall, or 45 other support. 2 is the sheave carrier having a center block 3 which, in the present instance, has a rectangular opening 4. A headed bar extends into the opening from the front of the block and through a swivel

50 section 6 to which is attached the two members of the sheave bearing 7. The sheave 8 is mounted between the two sections of the bearing and on a pivot 9 in the form of a bolt. Extending into the rear of the center

55 block 3 is a bar 10 having a series of perforations 11 at its outer end for the pin 12 from which a counterbalance weight 13 is suspended. This weight tends to counterbalance the sheave and a portion of the rope when slack.

60 On the center block are two sets of lugs, the lugs of each set being spaced apart and pivoted to the lower set of lugs 14 is a strut 15 made of heavy flat iron. The lower end of this strut is shaped in the form of a 65 pivot 16, Fig. 5, and is bent at an angle so that it will pass vertically through a bracket 17 firmly secured to the wall, or other fixed support. The end of this pivot is threaded 70 for the reception of a nut 18. This construction allows the sheave carrier to turn on the bracket and also allows a certain pivotal movement, as shown by dotted lines in Fig. 1. Attached to the upper lugs 19 is a chain 20 which is secured to the wall by a U-bolt 75 21 or other fastening. This construction permits a movement indicated by dotted lines in Fig. 1.

80 By the above construction, it will be seen that the entire sheave support can turn laterally to a certain extent on either side of the centre, as indicated by dotted lines in Fig. 2, and the sheave support can accommodate itself to the rope as the strut and chain will allow the support to have free 85 movement, as indicated by dotted lines in Fig. 1. The balance weight will tend to maintain the sheave, and its bearing, in substantially a horizontal position. In some instances, a bar, similar to that forming the 90 strut 15, may be substituted for the chain 20, but it is preferred to use the chain as shown.

I claim:

1. The combination in a sheave support, 95 of a center block; a sheave at one end of said block; a weighted bar at the opposite end of the block tending to balance the sheave; a strut pivoted to the center block and extending at an angle; a fixed bearing 100 for the lower end of the strut; and a member connected to the upper portion of the center block and to a fixed point above the sheave support.

2. The combination in a sheave support, 105 of a center block; a swivel mounted at one end of the block; a sheave carried by the swivel; a bar projecting from the opposite end of the block; a counterweight on said bar; upper and lower lugs on the center 110

block; a strut pivoted to the lower lug and to a fixed bearing; and a chain attached to the upper lug and to a fixed support some distance above the sheave support so as to allow the sheave support to move laterally and to allow the counterbalance weight to hold the sheave in substantially a horizontal position.

3. The combination in a sheave support, 10 of a center block having a longitudinal socket opening; a headed bar extending into the front end of said opening and secured to the block; a swivel mounted on said bar; a sheave carried by the swivel; a bar ex-

tending into the rear end of the socket in the center block and secured to said block; a balance weight mounted on the bar, said center block having upper and lower lugs; a strut in the form of a bar pivoted to the lower lugs and terminating in a pivot pin 20 at an angle to the strut; a bracket having an opening through which the pivot extends; a fixed support for the bracket; and a chain attached to the upper lugs and to a bolt secured to the fixed support substantially the same distance above the center block as the bearing for the strut.

ROBERT H. BEAUMONT.
